UNITED STATES PATENT OFFICE.

EDWARD P. LENAHAN, OF PHILADELPHIA, PENNSYLVANIA.

CLOTHES-RECEPTACLE.

1,247,294.

Specification of Letters Patent. Patented Nov. 20, 1917.

Application filed August 31, 1917. Serial No. 169,058.

To all whom it may concern:

Be it known that I, EDWARD P. LENAHAN, a citizen of the United States, and a resident of Philadelphia, in the county of Philadelphia and State of Pennsylvania, have invented a certain new and useful Clothes-Receptacle, of which the following is a specification.

The principal objects of the present invention are to provide for the delivery of clothes, gowns and articles of apparel, as well as for the storage of the same, without permitting them to become rumpled or otherwise disadvantageously disturbed and without exposing them to dust, dirt or insects, including moths. Another object of the invention is to provide a clothes receptacle adapted to accomplish the desirable results above mentioned and of simple, reliable and comparatively inexpensive construction and of light weight and attractive appearance, and of ease and facility in operation.

The invention will be claimed at the end hereof, but will be first described in connection with the embodiment of it chosen from other embodiments for the sake of illustration in the accompanying drawings, in which—

Fig. 1, is an elevational view of a receptacle embodying features of the invention, showing some of the interior parts in dotted lines.

Fig. 2, is a similar view of the tray with the housing removed.

Fig. 3, is an end view of the receptacle looking upward in Fig. 1, and

Fig. 4, is a perspective view of the open end of the housing with the tray removed.

There is a rectangular housing having four closed sides, 1, 2, 3, and 4, and one closed end 5 having a small opening 6. This housing is open at its end 7. 8 are contractile inserts near the open end 7 of the housing and when present they serve to normally contract the opening at the end 7. Rubber is a sample of a material from which the inserts can be made. 9, is a tray insertible in and removable from the open end of the housing and it is closed on five sides and partly closed as at 10 on the sixth side near one end. At the other end the tray is provided with a hanger fitting 11 adapted to pass through the small opening 6. The hanger fitting includes a hook 12, shown as

provided with a closed spring bill, and this hook detachably engages a hanger 13.

In use the garment is appropriately placed upon the hanger or support 13 in such a way as not to unduly crease or mar it, and the hanger and the garment are laid in the tray 9 in such a way that the part 10 overlies the garment and the hanger is connected with the hook 12; thus the garment lies in the tray unrumpled and appropriately supported. The tray containing the garment is then inserted into the housing through the open end 7 of the latter. This operation can be readily performed because it can be done on a flat table or other support. The hanger fitting 11 extends through the top of the housing and since the tray is closed on five sides and partly closed on the sixth side by a part 10, it follows that dust and insects are excluded. The accomplishment of the last named result is promoted by the contractile inserts, when present, because they tend to draw the walls of the housing into close contact with the walls of the tray which are near the open end 7 of the housing. The receptacle with the garment in it can be transported by means of the attachment 11, which for this purpose may be connected with a suitable fixture in a delivery wagon or van, and upon arrival at the destination the clothes can be readily removed from the receptacle and will be found to be uncreased and in perfect order by simply opening the receptacle and disconnecting the hanger from the fitting, and then hanging the hanger in any appropriate cupboard or closet. Of course if desired the garments may be removed from the hanger. The receptacle may then be sent back to the shop or factory from which the goods were delivered.

If desired the garments may be kept in the receptacle which can be hung up in an appropriate cupboard or closet or otherwise stored until the garments are wanted. When this is done the receptacle prevents the garments from rubbing against or contacting with other garments and in this way rumpling or mussing is obviated.

The receptacle in its parts may be made of light material, such as paper-boards and it is therefore light and cheap, while yet durable and attractive in appearance.

The receptacle is, of course, capable of reuse either by the merchant or the purchaser.

For the reasons stated, garments kept in the described receptacle, when not in use, retain the original form into which they have been pressed and so always look well when worn.

It will be obvious to those skilled in the art to which the invention relates that modifications may be made in details of construction and arrangement, for example, in order to suit the receptacle to different kinds of garments; hence the invention is not limited as to those matters or in any way other than the prior state of the art and the appended claims may require.

What I claim is:

1. A clothes receptacle comprising the combination of a generally rectangular housing having four closed sides and one open and one closed end and having in its closed end a small opening, and a tray in-

sertible in and removable from the open end of the housing and closed on five sides and partly closed on the sixth side near one end to in connection with the housing form a tight closure and provided at the other end 25 with a hanger fitting adapted to pass through said small opening.

2. A clothes receptacle comprising the combination of a generally rectangular housing having four closed sides and one 30 open and one closed end and having in its closed end a small opening and near its open end contractile inserts, and a tray insertible in and removable from the open end of the housing and closed on five sides and partly 35 closed on the sixth side near one end and provided at the other end with a hanger fitting adapted to pass through said small opening.

EDWARD P. LENAHAN.
